(57) **CLAIM**

The ornamental design for a spinning reel foot and stem, as shown.

DESCRIPTION

FIG. 1 is a perspective view from palm side of a spinning reel foot and stem showing our new design; FIG. 2 is a front elevational view thereof; FIG. 3 is a right side elevational view thereof; FIG. 4 is a left side elevational view thereof; FIG. 5 is a rear elevational view thereof; FIG. 6 is a top plan view thereof; and, FIG. 7 is a bottom plan view thereof.

The broken line showing of environment in the drawings is for illustrative purposes only and forms no part of the claimed design.

UNITED STATES PATENT AND TRADEMARK OFFICE
CERTIFICATE OF CORRECTION

PATENT NO. : Des. 443,019 S
DATED : May 29, 2001
INVENTOR(S) : Kang et al.

Page 1 of 9

It is certified that error appears in the above-identified patent and that said Letters Patent is hereby corrected as shown below:

The Title page, showing an Illustrative figure, should be deleted and substitute therefore the attached title page.

Delete the drawing sheet(s) 1-7 of 7, and substitute therefore the drawing sheet(s) consisting of Fig(s) 1-7 as shown on the attached pages.

Signed and Sealed this

Twenty-seventh Day of May, 2003

JAMES E. ROGAN
Director of the United States Patent and Trademark Office
